UNITED STATES PATENT OFFICE.

VICTOR R. DESPARD, OF HINSDALE, ILLINOIS, ASSIGNOR, BY MESNE ASSIGNMENTS, TO MCGILL MANUFACTURING COMPANY, OF VALPARAISO, INDIANA, A CORPORATION OF INDIANA.

SOCKET AND SHELL CAP FASTENING.

Application filed July 21, 1917. Serial No. 182,082.

To all whom it may concern:

Be it known that I, VICTOR R. DESPARD, a citizen of the United States, residing at Hinsdale, in the county of Du Page and State of Illinois, have invented a certain new and useful Improvement in Socket and Shell Cap Fastenings, of which the following is a full, clear, concise, and exact description, reference being had to the accompanying drawings, forming a part of this specification.

My invention relates to socket and shell cap fasteners, more particularly of use in connection with electrical devices. In one form of my invention which is the one chosen for illustration herein, my improved socket and shell cap fastener is of particular utility in connection with electric sockets which may for instance be of the customary Edison screw base type.

In this particular form of the invention there is provided a cover cap and what may be called a shell part, the two parts together forming the outside enclosure for the current carrying parts or movement within.

My invention contemplates the provision of means for readily causing the engagement of the shell and cap when the two parts are pressed together into their operative form, and further contemplates the provision of means whereby the shell and cap may be readily separated should it be desired to have access to the interior parts enclosed thereby. The engaging means between the shell and cap are of such a nature that they prevent when in operative condition both longitudinal separation between the parts and rotative movement between the parts. The engaging means are of such a character that the shell and cap may be brought into locked operative position in any one of a plurality of different relative angular positions.

I will explain my invention more in detail by referring to the accompanying drawings illustrating the same, in which—

Fig. 1 is a side view of a socket structure constructed in accordance with my invention, portions being broken away more clearly to reveal features of construction;

Fig. 2 is a side view of the cap;

Fig. 3 is a side view of the shell;

Fig. 4 is a top view of the shell;

Fig. 5 is a perspective view of a modified form of shell;

Fig. 6 is a perspective view of a locking element;

Fig. 7 is a sectional view of the shell and cap, the shell being of the type shown in Fig. 5;

Fig. 8 is a sectional view on line 8—8 of Fig. 1; and

Fig. 9 is a perspective view of the porcelain base used to carry the movement.

Referring more particularly to Figs. 1, 2, 3, 4, 6, 8, and 9, I show a cap 10 and a shell 11 which may be locked together in any one of a plurality of relatively different angular positions. The cap has a rounded bead 12 which, when the cap and shell are together, encircles the bead 13 provided upon the shell. The shell is slotted as shown at 14 so that the shell may be collapsed when it is being inserted in the cap. The shell is also provided with a locking element 15 having a tongue 16. This locking element is preferably riveted to the shell as shown at 17. A locking element 15 also carries a finger piece 18 which projects outwardly of the shell through a hole 19 provided therefor. The spring action of this locking element 15 keeps the tongue 16 between the opposite edges 20 and 21 at the extremity of the slot 14.

When it is desired to insert the shell into the cap the finger piece 18 is pressed inwardly to withdraw the tongue 16 from between the faces 20 and 21, thus to permit collapse of the shell as it is being inserted into the cap. After the shell is placed into the cap the pressure against the finger piece 18 is withdrawn so that the tongue 16 resumes its normal position, thus preventing a collapse of the shell. Thus the bead 12 by encircling the bead 13 holds the shell in position within the cap. In order to prevent rotational movement relatively between the cap 10 and the shell 11, a portion of each is made octagonal having the faces 22, on the cap portion and the faces 23 on the shell portion. These faces 22 and 23 interlock when the shell is in place within the cap. Thus relative rotative movement between the cap and shell is prevented.

From this it will be understood that the shell may be inserted in any one of eight

different angular positions relative to the cap. The object of providing means whereby the shell and cap may be locked together in a plurality of different angular positions 5 is due to the necessity of accommodating for the actuating finger piece or lever by means of which the movement in the interior of the shell is actuated to control the connections. The shell must be provided with a slot 24 to 10 accommodate for the finger piece, this finger piece 25 being shown substantially as of the type illustrated in my co-pending application Serial No. 140,248, filed Jan. 2, 1917. Means must therefore likewise be provided 15 to prevent a collapse of the shell 11 due to the slot 24, and these means are preferably provided upon the porcelain base 26, which carries the movement or current conducting parts within the shell. This porcelain base 20 26 has a projection 27 preferably directly above the finger piece 25 so as not to interfere therewith. This projection 27 passes between the opposite faces of the slot 24 to prevent collapse of the shell. 25 Normally, in mounting sockets of this nature in position the cap may first be secured to some supporting structure, whereupon the lead in wires 28 and 29 are mounted in place upon the porcelain base 26 preferably 30 through the agency of screws 30 and 31. After this is done the shell must be mounted in position. In order to do this the finger piece 18 is actuated to press the tongue 16 inwardly, thus permitting the shell to collapse as the bead 13 passes through the lower restricted mouth 32 of the cap. At the same time, however, the projection 27 passes between the opposite end faces of the slot 24 and prevents collapse at that point. 35 The collapse of the shell may then preferably take place at the slot 14. As soon as the bead 13 has slipped into position within the bead 12, the finger piece 18 is released and the tongue 16 moves into position to lock 40 the shell and cap together as the shell can no longer collapse and the beads 12 and 13 prevent endwise separation. Likewise, the interlocking nature of the faces 22 and 23 prevents rotational movement. The porcelain base 26 is likewise provided with a cut-away portion 33 to accommodate the locking element 15 with its tongue 16 when it is 45 pressed inwardly. An insulating cylinder 34 of the customary type may be provided 50 as shown more clearly in Fig. 8.

In Figs. 5 and 7 I show a modified form 55 of the device in which I combine the octagonal structure of the faces 22 or 23 with the beads 12 or 13 so that the cap 10^a has an octagonal beaded lower extremity 22^a and the shell 11^a has the octagonal beaded upper extremity 23^a. The locking element can be 60 of the same nature as for the device previously explained. It will be noted that in 65 the structure thus shown in Figs. 5 and 7 the

beaded nature of the faces 22^a and 23^a prevents endwise separation and the octagonal nature of these faces prevents relative rotational movement. In either event the shell and cap may be secured together in eight 70 different angular positions relatively to each other.

From what has been thus described the nature of my invention will be readily clear 75 to those skilled in the art.

Having thus described means for carrying out my invention, what I claim as new and desire to secure by Letters Patent is:

1. In a structure of the character described the combination with two separable parts adapted when united to form an enclosure, one of said parts being collapsible, of cam faced inter-engaging means on said parts adapted to be placed in engagement when one of said parts in collapsed condition 80 is inserted in the other part, actuatable means carried by one of said parts to normally prevent collapse of the collapsible part when the two parts are in their engaged condition, said collapsible part having a slot, an insulating base within said parts, and means carried by said base to prevent collapse of said collapsible part at said slot.

2. In a structure of the character described the combination with two separable parts adapted when united to form an enclosure one of said parts being collapsible, of cam-faced inter-engaging means on said parts adapted to be placed in engagement when one of said parts in collapsed condition is inserted in the other part, actuatable means carried by one of said parts to normally prevent collapse of the collapsible part when the two parts are in their engaged condition, said inter-engaging means 95 being adapted to operatively engage in any one of a plurality of different angular positions, said collapsible part having a slot, an insulating base within said parts, and means carried by said base to prevent collapse of said collapsible part at said slot.

3. In a structure of the character described the combination with two separable parts adapted when united to form an enclosure, one of said parts being collapsible of inter-engaging cam faced beads on said parts adapted to be placed in engagement when one of said parts in collapsed condition is inserted in the other part, actuatable means carried by one of said parts to normally prevent collapse of the collapsible part when the two parts are in their engaged condition, said collapsible part having a slot, an insulating base within said parts, and means carried by said base to prevent collapse of said collapsible part at said slot.

4. In a structure of the character described the combination with two separable parts adapted when united to form an enclosure, one of said parts being col- 130

- lapsible, of inter-engaging cam faced beads on said parts adapted to be placed in engagement when one of said parts in collapsed condition is inserted in the other part, actuable means carried by one of said parts to normally prevent collapse of the collapsible part when the two parts are in their engaged condition, said inter-engaging beads having cooperating faces for holding said parts against rotation in any one of a plurality of different angular positions, said collapsible part having a slot, an insulating base within said parts, and means carried by said base to prevent collapse of said collapsible part at said slot.
5. In a structure of the character described the combination with two separable parts adapted when united to form an enclosure, one of said parts being collapsible, of inter-engaging means on said parts adapted to be placed in engagement when one of said parts in collapsed condition is inserted in the other part, actuable means to normally prevent collapse of the collapsible part when the two parts are in their engaged condition, said collapsible part having a slot, an insulating base within said parts, and means carried by said base to prevent collapse of said collapsible part at said slot.
6. A device of the character described comprising a cap having a circumferentially recessed bead, a slotted collapsible shell having an integral circumferential bead for telescopic insertion into locking engagement with the cap bead, said beads having rounded co-operating locking surfaces, means for engagement with the shell slot to normally prevent collapse of the shell and thereby prevent separation of the cap and shell, and manually operable means for rendering the last said means inoperative so as to permit a separation of the parts by collapse of the shell.
7. A device of the character described comprising a cap, a slotted compressible shell for telescopic insertion into and withdrawal from the cap, said cap and shell having circumferential co-operating cam shaped locking surfaces interengaging when the shell is in the cap but permitting said shell to be inserted and withdrawn from the cap by direct telescopic thrust and pull respectively, and manually operable means for preventing collapse of the shell whereby said locking surfaces normally prevent separation of the parts but whereby said manual means may be operated to permit collapse of the shell by a direct pull and separation of the parts.

In witness whereof I hereunto subscribe my name this 13th day of July, A. D. 1917,

VICTOR R. DESPARD.
